G. W. BURKE, JR

FIRE EXTINGUISHING APPARATUS FOR AIRCRAFT

Filed July 12, 1924

INVENTOR
George W. Burke Jr.
BY
Robert A. Young
ATTORNEY

UNITED STATES PATENT OFFICE.

GEORGE W. BURKE, JR., OF DAYTON, OHIO.

FIRE-EXTINGUISHING APPARATUS FOR AIRCRAFT.

Application filed July 12, 1924. Serial No. 725,595.

This invention relates to fire extinguishing apparatus particularly designed and intended for use on aircraft.

The object of the invention is to provide an improved holder for portable fire extinguishers, especially those of the pistol type, for securely and demountably carrying the same on the outside of an airplane fuselage without danger of loss in flight or when taking off and landing, no matter in what position or where the extinguisher is mounted.

The foregoing and other objects relating to details of construction are brought out in the course of the following detailed description, in which reference is made to the accompanying drawings wherein:

Fig. 1 is a side view of a pistol type portable fire extinguisher demountably carried in a holder constructed in accordance with the invention and connected detachably with the receiving end of the fire extinguishing system of the plane, as contemplated by the invention.

Fig. 2 is a front view of Fig. 1.

Fig. 3 is an enlarged elevational detail of the means for providing a detachable connection between the extinguishing system and the portable extinguisher, and

Fig. 4 is a diagrammatic view showing the application of the system to an airplane.

The portable fire extinguisher 10 utilized as a part of the system herein contemplated is of the pistol grip type, the details of construction of which are described and claimed fully in applicant's previous application, Ser. #688,480, filed Jan. 25, 1924. Briefly, the extinguisher comprises a barrel 11 of a cylindrical form preferably, mounted on a pistol grip 12 and having a discharge nozzle 13 through which extinguishing fluid is expelled under pressure when the trigger 14 is depressed. Upon depression of the trigger, a cartridge within the breech 15 containing a compressed gas, is ruptured, and supplies the pressure medium for expelling the extinguishing fluid from the barrel 11 through the nozzle 13. A hollow stem 16 joins the nozzle 13 with the barrel 11 and a valve 17 operated by the trigger 14 controls the flow of fluid from the nozzle 13.

The extinguisher, when removed from the holder 18, is capable of directing a stream of extinguishing fluid to practically all exposed portions of the airplane, whether the

fire originates on either of the wings or at any point on the fuselage or tail. Where a fire originates in a concealed portion of the plane, as for example, beneath the cowling 19, extinguishing fluid is sprayed on it from nozzles 20 at the discharge end of a conduit 21 having its receiving end adjacent the holder 18 and detachably connected with the nozzle of the extinguisher. The conduit 21 is coupled at 22 with a connection 23 supported in a bracket 24 secured to a convenient portion 25 of the airplane fuselage on which the holder 18 is also mounted. The bracket 24 is provided with a cam faced projection 26 which is arranged to engage the rear side of the stem 16 on the extinguisher to cause the nozzle 13 to engage wedgingly with a gasketed portion 27 on the end of the connection 23 to provide a fluid and pressure tight joint.

The holder 18 is in the form of a bracket having two open-sided parallel approximately semi-circular spring clips 28 which partly embrace the cylindrical barrel 11 when the extinguisher is carried in the holder. A pair of wire links 29 of a substantially U-shape are pivoted at 30 at the same end of each of the clips 28 and bridge the gaps between the ends of the clips at points longitudinally spaced on the barrel 11 on opposite sides of the pistol grip extending laterally from the barrel 11. A bar 31 extending longitudinally of the barrel 11 is slideable on the links 29 toward the outwardly bent portions 32 on the clips 28 under the action of springs 33 acting between the ends of the bar 31 and plates 34 secured to the ends of the links 29. A pair of end clips 35 confine the barrel 11 against endwise movement. With this arrangement, the extinguisher is securely held against loss in flight or when taking off and landing, no matter in what position or where the extinguisher is carried. When it is desired to remove the extinguisher for refilling, or in the event of a fire on some exposed portion of the plane, the grip 12 is clasped and in so doing, the extinguisher is rotated on the barrel 11 as an axis and the bar 31 yields and rides over the outwardly bent ends 32 of the clips 28 whereupon the extinguisher is removable by simply drawing the same outwardly.

The detachable connection between the extinguisher and the conduit 21 permits the

ready replacement and removal of the extinguisher from the holder. The cam projection 26 engages behind the stem 16 and makes a proper fluid-tight joint between the extinguisher and the conduit 21 as the extinguisher is placed in the holder. It has been found desirable to enable the pilot, after pulling the trigger 14, to initiate the discharge of the extinguisher, to pay no further attention to the matter of discharging the extinguishing fluid into the system through the conduit 21, but to resume full control of the plane, in an effort to make a safe landing, if that is desired. For this purpose, a latch 36 pivoted at 37 above the trigger 14 is provided to drop down and engage in front of the trigger 14 under the action preferably of a light spring 38 and lock the trigger in the dotted line position indicated with the valve 17, in open position. The latch 36 has a lateral projection 39 which can be engaged and moved by the finger in operating the trigger 14 so that the trigger can be unlocked at will.

From the foregoing description, it will be apparent that I have provided a system of a unique character capable of combating fire originating at any point on the plane and from any cause. The portable extinguisher forming a part of the system is quickly removable to extinguish fires other than those which the system itself is arranged to have under control and the extinguisher is available for fires other than those arising on the plane itself so that the device could be used in the event of a fire breaking out in the hangar. The holder which securely and demountably carries the extinguisher usually on the outside of the fuselage adjacent the cockpit, is particularly adapted for use in connection with the system described, but may be used apart from a system on planes not provided with such an installation.

I claim:

- 45 1. A holder for an article having a lateral projection, comprising an open-sided clip to embrace the article, a bar hingedly connected with a prong of the clip lying in the path of movement of said projection on said article when the latter is rotated in the clip to be moved by said projection and afford egress for said article from said clip.
- 50 2. A holder for an article having a lateral projection, comprising an open-sided clip to partly embrace the article, and having a closure to complete the embrace of the article, rotation of said article in said clip causing said projection to open the clip and permit the removal of the article therefrom.
- 55 3. A holder for a pistol grip fire extinguisher, comprising open-sided clips to embrace the barrel of said extinguisher at points spaced lengthwise thereof, a bar extending lengthwise of the barrel as it is held in the clips hingedly connected by links at

the ends with the same end of each of said clips on the same side of the barrel, said bar being yieldably held at each end by the free end of each of said clips to be swung free and out of the way by engagement of the pistol grip on said extinguisher in the turning thereof in the clips to permit the removal of said extinguisher.

4. A holder for a pistol grip fire extinguisher, comprising a bracket, a pair of end members thereon to confine the ends of the barrel of said extinguisher, a pair of parallel open-sided clips to partly embrace the barrel from the side at points spaced lengthwise thereof, a bar extending lengthwise of the barrel as it is held in the clips connected at the ends with the same end of each of said clips on the same side of the barrel, said bar being movable by engagement of the pistol grip on said extinguisher in the turning thereof in the clips to permit the removal of said extinguisher.

5. A holder for a pistol grip fire extinguisher, comprising a bracket, a pair of end clips thereon to confine the ends of the barrel of said extinguisher, a pair of open sided circular clips to snap over and partly embrace said barrel from the side at points spaced longitudinally thereof, a pair of links bridging the gaps between the ends of the clips pivotally connected to the same end of each of said clips on one side of the barrel, said clips having the opposite ends on the other side of the barrel bent outwardly to form abutments, a bar mounted on said links and held under the action of springs on said links behind said abutments and extending longitudinally of the barrel and in the path of movement of the pistol grip thereon to be moved in the movement of the latter when said extinguisher is turned in the holder.

6. A holder for a pistol grip fire extinguisher, comprising open sided clips to embrace the barrel of said extinguisher at points spaced lengthwise thereon, a conducting pipe fixed to said holder, and means arranged to secure a wedging engagement of the extinguisher outlet and said pipe in the movement of the extinguisher about its longitudinal axis in mounting the extinguisher in said holder.

7. A holder for a pistol grip fire extinguisher, comprising open sided clips to embrace the barrel of said extinguisher at points spaced lengthwise thereon, a conducting pipe fixed to said holder, and means arranged to secure a wedging engagement of the extinguisher outlet and said pipe in the movement of the extinguisher about its longitudinal axis in mounting the extinguisher in said holder, comprising a cam member mounted on said holder and a part on said extinguisher engageable therewith.

8. A holder for a pistol grip fire extin-

guisher, comprising open sided clips to embrace the barrel of said extinguisher at points spaced lengthwise thereon, a bar extending lengthwise of the barrel as it is held in the clips and resiliently connected at its ends to the clips, said bar being mounted to be swung free and out of the way of the extinguisher by engagement of a pistol grip thereof in the turning movement of the extinguisher in the clips about the longitudinal axis of the extinguisher to permit the removal of said extinguisher. 10

In testimony whereof I affix my signature.

GEORGE W. BURKE, JR.
